ABSTRACT OF THE DISCLOSURE

The pressure in a vessel is transformed into an analogue signal which is applied to a comparison network to be compared with another signal varying according to a predetermined program. The resulting difference signal controls through electromechanical control means a valve at the inlet of the vessel. A correction circuit coupled with said valve produces a compensation signal which is fed back to said electromechanical means to insure correct controlling action of said valve.

The present invention relates generally to an apparatus for automatically and simultaneously controlling the time and the pressure in a casting process, and it relates more particularly to an apparatus for automatically controlling the pressure as a function of time in a low-pressure die casting process.

The present application is a continuation-in-part of 35 our co-pending application Ser. No. 325,823, filed Nov. 25, 1963 and now abandoned.

The present invention relates generally to an apparatus for automatically controlling the pressure in a vessel. More particularly, the present invention relates to an apparatus for automatically controlling according to a predetermined program a fluid pressure in a vessel for a die casting process.

In low-pressure die casting processes, especially when the object being cast has an excessively elongated form, and if the metal being used has a large specific gravity, the pressure over the molten metal in the melting vessel becomes excessively reduced when the air in the mold is sucked out through the upper part of the mold while the molten metal is sucked into the mold. Therefore, it becomes necessary to supply additional pressure to the surface of the molten metal in the vessel. However, after completion of the solidification of the molten metal in the mold, and before the molten metal would be allowed to solidify in the feeding pipe, the additional pressure applied to the surface of the molten metal in the mold should be reduced back to the atmospheric pressure so that the molten metal which is in the feeding pipe could return into the vessel. In low-pressure die casting processes, especially in the cases mentioned above, when the object being cast has an excessively elongated form, it becomes very difficult to control the speed of rising and the speed of solidification of the molten metal. Therefore, the above described so-called "suck-in and pressurize" method of casting has not been put into practice so far for the difficulties encountered therein.

In a low-pressure die casting system it may be required that the initial pressure be applied to the surface of the metal in the vessel and then be raised slowly by approximately 0.4 kilogram per square centimeter within a specified time interval, which may be a period of time between 20 and 120 seconds. The pressure may be kept

2

at a second value of between 0.7 and 1.0 kg./cm.² for a second time interval. Since the two time intervals and the fixed pressure values must be controllable, means must be provided to set the different values of pressure and the time intervals according to the desired operation.

Formerly such operations were performed by manually controlling the opening of the pressure feeding valve. In such an operation, it is very difficult to control the pressure at the desired value; and there are other deficiencies in this former operation such as that the quality of the castings is not uniform because the pressure tends to be forced in a short time, and the operation cannot be repeated with the same degree of accuracy over a number of casting cycles.

15 It is, therefore, an object of the present invention to provide an improved apparatus for automatically controlling the pressure as a function of time in a low-pressure die casting process.

It is another object of the invention to provide an 20 apparatus by which the pressure over the molten metal is controlled in accordance with a predetermined program, and by which any deviations from the pressure set by the predetermined program are instantaneously corrected.

25 It is still another object of the present invention to provide a programming means for an apparatus controlling the pressure in accordance with a predetermined program in a low-pressure die casting process, in which the desired pressure conditions are attained by simple and reliable 30 mechanical means.

It is still a further object of the present invention to provide in an apparatus controlling the pressure conditions in a low-pressure die casting system a programming means of simple mechanical nature which is correlated with a timing apparatus and which produces a reference signal representing the desired pressures as a function of time.

In accordance with the invention, in a control apparatus 40 for controlling the gas pressure in a vessel, a pneumatic circuit is provided which connects the vessel to a pneumatic source, pressure sensing means on the vessel for producing a signal in response to the instantaneous pressure existing in the vessel, and a programming means which produces an output signal representative of a predetermined pressure as a function of time, and also control means 45 which respond both to the output of the pressure sensing means and to the output of the programming means and are adapted to compare the aforesaid outputs to provide a balance signal in response to a difference between the aforesaid outputs and to effect the instantaneous position 50 of a valve means disposed in the aforementioned pneumatic circuit and regulate the valve means either to permit the flow of pressurized fluid to the vessel or to restrict the flow of pressurized fluid as flowing to the vessel in dependence of the sign of the balance signal.

The invention also provides in the pressure control apparatus that the programming means includes a rotatably mounted disc with which a timing element is coupled so that rotation of the disc, as controlled by the timing element, produces an output signal which represents a pressure-time signal which is used as a reference signal to compare same with an output signal from the pressure sensing means.

In accordance with the invention the aforementioned 60 programming disc is mounted for rotation on a fixed axis and the outer edges of the disc are placed at different distances from the center thereof, so that the edge portions of the disc sweep a varying area with respect to the center of the disc. That is, if the edge portions of the program disc are traced by a lever, which is pivotally mounted at a fixed point and the free end of which is adapted to ride on the edge portion of the program disc, the free end of

the pivotable lever will sweep an area which if projected on a time axis corresponding to the time required by the disc to complete one revolution will be bounded by curve representing a time-pressure function. The shape of the disc is made in accordance with the desired time-pressure curve. The disc is interchangeable to enable the attainment of any desired time-pressure curve by the control apparatus in accordance with the invention.

In accordance with the invention, the lever is coupled with its free end in tracing relationship with the edge portions of the disc and has connected thereto and to move therewith a wiper arm of a potentiometer, which potentiometer develops an electrical signal representative of the predetermined pressure desired in the particular operation. The pressure sensing means connected to the vessel provide a signal representative of the instantaneous pressure above the molten metal and such signal is fed to drive a servo-motor which in turn operates the wiper arm of another potentiometer and develops a signal thereon representative of the instantaneous pressure in the vessel. The first mentioned and the last mentioned potentiometers are arranged in a bridge circuit, that is, a voltage appearing at their respective wiper arms is compared and fed into subsequent circuits adapted to respond to a balance between such voltages on the wiper arms, so that a servo-motor is actuated by the balance in the direction depending upon the sign of such balance, to operate a valve set in a pneumatic circuit connecting the vessel to a pneumatic source and causing the pneumatic circuit to be restricted or opened in accordance with the signal fed to the servo-motor operating the valve.

The invention will become more readily apparent from the following description of a specific embodiment thereof shown, by way of example, and illustrated in the accompanying drawings, in which:

FIG. 1 is a diagrammatic showing of the principles of operation of the control apparatus of the present invention;

FIG. 2 is a circuit diagram showing the circuit for developing a reference signal by the programming means and its comparison with the instantaneous signal developed by the pressure sensing means and their conduction to the valve controlling servo-motor;

FIG. 3 is a circuit diagram showing a bridge circuit for developing a signal in response to the pressure sensing means;

FIG. 4 is a circuit diagram showing the connection of the programming means and the respective valve means;

FIG. 5 is a diagrammatic showing of the disc of the programming means with its associated tracing lever in several operating positions; and

FIG. 6 is a pressure-time diagram representing the reference pressure as traced out by the lever engaging the program disc.

With reference to the drawings, particularly to FIG. 1, it is seen that the pressure vessel 1 containing a molten metal has a pneumatic circuit arranged therearound, in which the branch of the circuit designated by the reference character P connects the vessel to a source of pneumatic pressure (not shown), whereas the branch of the pneumatic circuit designated by P' connects the vessel 1 through a valve V₃ to the atmosphere in a manner hereinafter described. The pneumatic circuit branch P contains a valve V₂ which has only a fully opened and a fully closed position and is operated by a solenoid upon certain conditions in the operating stage of the control apparatus as hereinafter described. The circuit branch P contains a servo-motor operated valve MV which is actuated by appropriate manner hereinafter described by the controlling means shown as block C in FIG. 1 in response to a correcting signal developed by the controlling means C as need may arise to permit or restrict the flow of pressurized fluid in circuit branch P to the vessel 1 in accordance with the type of pressure conditions existing in vessel 1 sensed by pressure sensing means F which is

operatively connected to the controlling means C for comparing the instantaneous pressure sensed by it. An indicator 10 is placed in cooperation with the controlling means C to indicate the instantaneous pressure in the vessel and which also actuates a switch S₁ for purposes hereinafter described. Another indicator I may be placed upstream of the motor valve MV to indicate the pressure supplied by the pressure source (not shown).

Referring now to FIG. 2, it is seen that the vessel 1 containing the molten metal which is to be raised into a die (not shown) by supplying pressurized fluid to the vessel from a source of pneumatic pressure through pneumatic circuits as shown in FIG. 1, has a pressure sensing device connected thereto which includes a pressure sensing tube F which is preferably of the Bourdon-type tube well known in the art and which is adapted to produce mechanical movements as its output in response to the pressure variations within the vessel. The mechanical movements produced by the Bourdon tube are translated into electrical signals by means of a transducer 19, such as a differential transformer having a movable core responsive to the mechanical movements produced by the Bourdon tube and which transformer produces an output representative of the pressure variations within the vessel. Other transducers than a differential transformer are possible, such as a piezo-electric transducer, the output of which would be also representative of the pressure variations in vessel 1. The output of the differential transducer 19, or of a similar transducer, is fed into a servo-motor (not shown) the rotation of which operates a linkage 11 which is connected to a wiper arm B of a balanced bridge circuit 20. The balanced bridge circuit 20 being shown in more detail in FIG. 3 includes a pair of resistance branches 21, 22 connected across a voltage source V into a balanced bridge circuit. Resistor 22 has the wiper arm B slidably associated therewith which, as aforementioned, is operated by linkage 11 in response to the output of the transducer 19 through the servo-motor. The resistor 21 has a wiper arm A slidably associated therewith and which is operable by a servo-motor 24 at the output of the bridge circuit 20 to balance bridge circuit 20 in a known manner. As more clearly seen in FIG. 3, when wiper arm B is moved in the direction of I or II in dependence of decreasing or increasing pressures in the vessel 1, then the bridge becomes unbalanced and, such unbalance in dependence of the direction of movement of wiper arm B may have a sign of (+) or (-) and have a magnitude e which is fed into amplifier 23 to the output of which the servo-motor 24 is connected. The servo-motor in accordance with the sign of the output e rotates in a direction corresponding to such sign, and with a feedback arm 25 operates wiper arm A sliding on resistor 21 to balance the bridge in a known manner by moving wiper arm A in the direction of III or IV depending of the direction of movement of the wiper arm B. The servo-motor 24 represents with the direction and time of its rotation the output e of the balanced bridge circuit 20 (which as aforesaid is representative of the pressure variations in vessel 1), and is connected to operate a wiper arm 31 of a control means preferably comprising a bridge circuit 30. The wiper arm 31 of the bridge circuit 30 is adapted to slide on a resistor 33 and in response to the movement imparted thereto by the servo-motor 24 develops a voltage e_1 which is representative of the instantaneous pressure within vessel 1, and which voltage is compared with another voltage representing the desired pressure conditions in the vessel as hereinafter described.

As pointed out above, it is desired that the pressure within the vessel 1 over the molten metal body should be maintained at different magnitudes during different time intervals according to the type of casting to be made and the material used in the casting process. In order to attain and maintain the required pressure magnitudes, a programming device is provided which produces a signal

representative of the desired pressure as a function of time. The programming device includes the programming disc 6 shown in more detail in FIG. 5, which is fixedly mounted for rotation by a motor 7 through a timing device T. As seen in FIG. 5, the program disc 6 is adapted to rotate about an axis of mounting O. A lever 9 pivotally secured at point O' and having a free end 36 engages the edge portions of the disc 6, and when the disc rotates the lever sweeps a varying area which is a function of the instantaneous distance of the free end 36 of lever 9 from the origin O of the program disc 6. That is, by drawing an infinite number of radii from origin O of the disc to different portions of arc a-b, and taking the radius at point a as having a value of zero, it is seen that the radii increases as the free end 36 of the lever 9 moves toward the point b. The free end of lever 9 then describes the pressure curve portion a-b which is seen in FIG. 6 and lasting during the time interval t_1 . By following the free end 36 of the lever 9 from the point b to c on the program disc, it is seen that the radii which could be drawn from the origin O of the disc to any point of the arc b-c, are constant, therefore, the lever 9, that is its free end 36, describes a curve corresponding to portion b-c in FIG. 6 and lasting during the time interval t_2 . The spacing of the free end 36 of the lever arm 9 from point c to d produces the curve portion c-d in FIG. 6 lasting during the time interval t_3 . The lever arm 9 is connected through an arm 35 to a wiper arm 32 which is adapted to slide on resistor 34 of bridge circuit 30 and develop a voltage e_2 which is representative of the pressure conditions desired and as shown in FIG. 6. The invention provides that the program disc is interchangeable and any desired pressure condition can be programmed with the apparatus of the invention by mounting a different program disc onto the axis O. The calibration of bridge circuit 30 is such that if the pressure represented by the voltage e_1 is equal to the desired pressure represented by the voltage e_2 , then the bridge 30 is balanced and no output voltage is developed across its terminals 40, 41. However, if the instantaneous pressure represented by the voltage e_1 is larger or greater than the desired pressure represented by the voltage e_2 then a difference voltage is developed across terminals 40, 41 which then, through various networks such as shown diagrammatically by blocks 3, 4 and 5, is connected via an amplifier 43 to a servo-motor M which operates the setting of valve MV. The servo-motor M is further mechanically coupled with a corrective bridge leg 42 which produces a balance voltage e_3 as a function of position of the valve MV. This balance voltage e_3 is fed back to the input stage 4 to compensate the difference voltage applied to the terminals 40 and 41. In accordance with the sign of the balance voltage e_3 , developed between terminals 40, 41, the servo-motor is driven to increase opening of the valve MV or to restrict the flow of pressurized fluid through pneumatic circuit P when driven in the opposite direction.

During operation of the control apparatus, a start switch MS is closed along with a switch S₂ which connects motor 7 of the programming means to energizing power source V_S, while timer T is energized through the closing of switch S₁ concurrently and starts at t_0 as seen in FIG. 6. Energization of timer T closes auxiliary switch S₃. The closing of starting switch MS connects the energizing coil of a solenoid R to source V_S and by being energized, the solenoid R closes contact pair 50, 51 and contact pair 52-53, while at the same time opens contact pair 54, 55, whereupon the solenoid of valve V₃ is deenergized which closes valve V₃ preventing exhaustion of pressure from vessel 1 through circuit P' and the solenoid of V₂ is energized which opens the valve V₂. Valve V₂ is now fully opened and permits pressurized fluid to flow from the source (not shown) through pneumatic branch P. Upon energization of the solenoid V₁ by closing switch S₁ the by-pass valve V₁ is closed whereby the flow of pressurized fluid from the pneumatic source is controlled only by

the above-described behavior of the valve MV, since the valve V₂ is now fully opened, and the actuation of the timer at t_0 immediately closed auxiliary switch S₃. While the programming means goes through the time cycles shown in FIG. 6 with the valves being in the state as described in connection with FIG. 4, the ultimate control of the pressure in the vessel 1 proceeds in accordance with the operation described in connection with FIG. 2. As the pressure indicator 10 attains a set pressure which is represented by the curve at point d, the contact S₁ opens up whereupon the bypass valve V₁ opens and the timer is deenergized. Deenergization of the timer T opens up auxiliary contact S₃, whereupon the solenoid R becomes deenergized and the solenoids of valve V₃ and V₂ are reverted in the initial state, that is, the valve V₃ opens and connects the vessel 1 to the atmosphere and the valve V₂ closes preventing pressurized fluid from entering vessel 1 from the source (not shown). The programming disc 6 rotates further since its motor 7 is still energized due to the fact that the contact S₂ does not open until the programming disc completes a full revolution and returns to its original state, whereupon S₂ opens and deenergizes the motor 7.

It is seen that the apparatus in accordance with the invention provides reliable automatic control of the pressure in the vessel and maintains it in accordance with a predetermined pressure program.

What is claimed is:

1. An apparatus for automatically controlling the fluid pressure in a vessel according to a predetermined program, comprising a pressure conduit circuit including a branch for connecting said vessel to a pressure fluid source; valve means provided in said conduit branch to control fluid supply to said vessel; means for sensing the pressure in said vessel and producing a first analogue signal in response thereto; programming means having a rotatable disc, the periphery of which is profiled according to the desired pressure function; means for controlling the time of rotation of said profiled disc, follower lever means engaging said profiled periphery and adapted for deriving a second analogue signal representing said predetermined pressure as a function of time; comparison means adapted to compare said first and second signals and to produce a differential signal therefrom; valve control means provided between said comparison means and said valve means to control the latter in response to the sense and magnitude of said differential signal; and balancing means adapted to produce a third signal analogue to the position of said valve means, said third signal being fed back to said valve control means to compensate said differential signal.

2. Apparatus as claimed in claim 1, wherein said comparison means comprises at least a pair of resistor means connected into a balanced circuit, varying means associated with each of said pair of resistors to shunt variably a portion of said resistor, the varying means of one of said resistor means being coupled to said lever means to move in proportion therewith.

3. Apparatus as claimed in claim 2, wherein said pressure sensing means includes a transducer means producing an output representative of said pressure variations, means responsive to the output of said transducer means, the last-mentioned responsive means being coupled to the varying means of the other of said pair of resistors for imparting a movement to said varying means proportional to the pressure variations in said vessel.

4. Apparatus as claimed in claim 3, wherein the last-mentioned responsive means includes a phase sensitive bridge circuit having an output the phase of which varies in its sign in accordance with the variation of the pressure in said vessel.

5. Apparatus as claimed in claim 4, wherein the last-mentioned responsive means further includes a servomotor coupled to the output of said phase sensitive bridge circuit.

6. Apparatus as claimed in claim 5, wherein said transducer means is a differential transformer having a core movable in accordance with the pressure variations in said vessel.

7. Apparatus as claimed in claim 6, wherein said conduit circuit includes another branch, second valve means disposed in said another branch for connecting said vessel to the atmosphere when activated.

8. Apparatus as claimed in claim 7, wherein said disc means has associated therewith switch means, means for driving said disc means in cooperation with a timing means, said disc means effecting disconnection of said switch means upon a complete revolution thereof, said switch means disconnecting the driving means upon said complete revolution.

9. Apparatus as claimed in claim 8, wherein said second valve means has associated therewith solenoid means disposed in an energizing circuit of the driving means, said solenoid means opening said second valve means upon said complete revolution.

10. Apparatus as claimed in claim 9, including further valve means disposed in said one branch of said pneumatic circuit upstream of said valve means for permitting full

flow of fluid thereto when actuated upon energization of the driving means.

11. Apparatus as claimed in claim 10, wherein said solenoid means comprises a common actuating member for said second valve means and said further valve means.
